UNITED STATES PATENT OFFICE.

FREDERICK A. EUSTIS, OF MILTON, MASSACHUSETTS.

SINTERING APPARATUS.

1,212,833.

Specification of Letters Patent. Patented Jan. 16, 1917.

Application filed August 18, 1915. Serial No. 46,031.

To all whom it may concern:

Be it known that I, FREDERICK A. EUSTIS, a citizen of the United States, and resident of Milton, in the county of Norfolk and State of Massachusetts, have invented new and useful Improvements in Sintering Apparatus, of which the following is a specification.

This invention relates to apparatus for sintering fine ores of lead, zinc, copper, iron and other fine materials, by which the small particles are agglomerated into a solidified mass. The sticking together of fines is desirable in many metallurgical operations.

The sintering process, to describe it generally, consists in subjecting the fine ore, mixed with a certain proportion of fine fuel, to a burning or roasting treatment, by which the small particles are fused and aggregated into a porous mass. This process is usually carried on in a sintering pan in which a bed of the material is held while the combustion of the fuel mixed with the ore takes place, and it is the object of the present invention to improve the construction of sintering apparatus, and render the same more efficient, and economical in operation.

In the accompanying drawings which illustrate the invention, Figure 1 is an end elevation of one sintering unit containing the invention, arranged in a building which will preferably contain a series of similar units; Fig. 2 is a plan view, partly broken away, showing one of said units on an enlarged scale; Fig. 3 is a cross section on line 3-3 of Fig. 2; Fig. 4 is an enlarged detail, partly in side elevation and partly in section, of one of the pneumatic latch operating devices for the cover; and Fig. 5 is a view illustrating a modification.

The sintering plant comprises a suitable building 1, in which a series of sintering units are arranged in a row so that they may all be supplied with material from a car 2 which runs on overhead rails 3 above the several units. Each unit consists of a fixed pan 4, having an open bottom and an open top, mounted on suitable supports in the building. 5 is a cast iron lining for the walls of the fixed pan to prevent the heat from warping or injuring the structural steel of which the pan is made.

At the bottom of the fixed pan 4, are the grate 6 and under pan 7, assembled to move as one part, and pivoted to the fixed pan

at 8 to swing downward to the positions shown in dotted lines.

The top of the fixed pan 4 is closed by a cover 9, which swings upward to dotted line 63 position (Fig. 1) on hinges 10, having their pivots at 11, somewhat in the rear of and below the pan, so that the cover when open will be clear of the pan and out of the way of the car 4.

The cover 9 and fixed pan 4 are provided with mutually engaging flanges 12 and 13, clamped together by a series of pneumatically operated locks. Each such lock consists of a projection or socket member 14, 70 secured to and projecting upwardly from flange 13, and a bolt or latch member 15, movable lengthwise of flange 12 into and out of a hole or recess in the socket member 14. The bolt member of each lock is operated by 75 a lever 16, pivoted to the bolt and to the cover 9, which lever is in turn operated by a piston rod 17, connected to piston 18 in a pneumatic cylinder 19. Two air pipes, 20 and 21, communicate with cylinder 19 at opposite sides of the piston, and as the lock opening pressure is exerted on the entire area of the piston 18, while the closing pressure is exerted only on the area of the piston less the cross sectional area of the piston 85 rod, the effective force for opening the lock will be greater than that for closing it, thus insuring the release of the bolts. Said air pipes are supplied through pipes 21^a from a suitable source of air pressure, and are controlled by valves at some convenient station, 90 22, where the operator may stand.

The cover 9 is counterweighted by means of a weight 23, carried on an arm 24. The arm 24 also serves as an operating arm for 95 opening and closing the cover, and is actuated by a pneumatic operating device, consisting of a cylinder 25, containing a piston 26, which moves a piston rod 26^a, pivotally connected to arm 24. The cylinder 25 is 100 mounted to swing on a pivot 27. When the piston and piston rod are projected the cover will be closed, as shown in solid line position; when the piston and piston rod are retracted the cover will be opened, as shown in 105 dotted line position. The piston 26 is operated by suitable air pipes 28, which deliver compressed air to the cylinder 25 at opposite sides of the piston, and are controlled by valves at station 22. In a similar manner 110 the grate 6 and under pan 7 are operated by a pneumatic cylinder 29, pivotally mounted

- at 30, and having a piston rod 31 connected to the under pan 7. The cylinder 29 is supplied with air by pipes 32, which are controlled by valves at the station 22. Air is forced into the pan through the air pipes, or bustle pipes 33, which enter through the side of the cover, and are connected through swivel joints 34 with a main air supply pipe 35, to which a blast of air is supplied by a suitable blower or pump (not shown).
- 36 is a gas pipe, connected to a cross head 37 within the cover 9, from which cross head project a number of branch gas pipes 38 to form gas jets for igniting the charge in the pan. The gas pipe 36 is connected, through swivel joint 39, to the main gas supply pipe 40.
- 41 is a water pipe connected to a cross head 42, from which the branch water pipes 43 extend, to deliver jets or sprays of water upon the material in the pan. The pipe 41 is connected through swivel joint 44 with a main water supply pipe 45. All of said swivel pipe joints have their axes coincident with the axis 11 of the cover hinges, so that when the cover is opened and closed all of the pipes in the cover are free to move with it. A smoke stack 46, secured to the wall of fixed pan 4, leads from the space in the under pan 7 below the grate.
- In operation the fine ore, with about 5% to 10% of fine fuel, forming the charge, is carried along in car 4 over one of the sintering units, the cover 9 is opened, and the charge is spread out in the pan on grate 6. The cover is then closed and locked by the pneumatically operated locking devices above described, which hold the cover tightly in place against the air pressure subsequently introduced into the closed pan. Air is forced in through the bustle pipes 33, and passes down through the charge and out through the stack. The charge is then ignited by means of the jets from the gas pipes 38, and after it is well ignited the gas is turned off. The products of combustion escape through stack 46. During the sintering process water is thrown on to the material in the pan from time to time as desired, through water pipes 43, while the fuel is burning. This substantially improves the sintering probably by keeping the temperature down. After the small particles of ore have been thoroughly fused together and the fuel burned out, the grate 6 and under pan 7 are swung down to dotted line position, and the agglomerated mass is dumped out into a chute 47, whence it is delivered into a suitable receptacle, such as a car 48, which may be on tracks outside of the building. Instead of dumping the metal down an inclined chute into a car outside, it may be dumped into a car immediately underneath the sintering pan as shown in Fig. 5. In this case the under pan must be arranged

to open wide, out of the path of the descending material, and will preferably be operated by a system of pulleys and cables instead of by pneumatic means.

With this apparatus a very material advantage is obtained by creating the down draft by introducing cold air under pressure above the material, as distinguished from applying suction below the material. When the draft is obtained by suction, the pump or blower has not only to handle a far greater volume of gas owing to its temperature, but it is subject to much more rapid deterioration by reason of handling a hot, dirty, moist gas. The blowing of cold air under pressure on top of the material saves nearly half the power required for producing the same draft, and at the same time results in a marked saving in wear of the blower.

It will be noticed that the right hand side of the under pan, as viewed in the drawings, that is, the side opposite the hinge, is open, whereby the dirt which falls through the grate 6 during the sintering process and lodges in the pan 7, will be dumped out when the pan 7 is swung down to dotted line position. When the pan 7 is in closed position its open side will be closed by the downwardly extending part of the side wall 4^a of the fixed pan. The stack 46 is fastened to the downwardly extending wall 4^a, so that it remains undisturbed when the under pan 7 is swung away from the fixed pan.

The structure of the downwardly swinging grate is also well adapted to the use of a water cooled grate, in which case some or all of the grate bars would be in the form of water pipes communicating with a water circulating pipe. The inlet and outlet of such water pipe grate bars should be located in the axis of the hinge of said grate and under pan, and should be provided with swivel joints connecting them with the water circulation pipe, precisely similar to the swivel joints in the pipes entering the cover.

I claim:

1. A sintering apparatus comprising a pan, a cover for said pan, and means to force air under pressure from a blower or air pump into said pan between the cover and grate, thereby to produce a downward draft of air through the charge on the grate.

2. A sintering apparatus comprising a pan, a cover for said pan, and means to force air under pressure from a blower or air pump into said pan between the cover and grate, thereby to produce a downward draft of air through the charge on the grate, and means to lock the cover in closed position.

3. A sintering apparatus comprising a pan, a cover for said pan, and an air pipe extending into the apparatus between the

cover and grate adapted to deliver air under pressure above the charge on the grate and thereby to produce a downward draft therethrough.

5 4. In a sintering apparatus, a sintering pan having a grate, a cover for said pan, a stack leading from below said grate, and an air delivery pipe extending into the apparatus between the cover and the grate adapted to deliver air under pressure above a bed of material on the grate, said air delivery pipe being movable away from its operative position over the grate.

10 5. In a sintering apparatus, a sintering pan having a grate, a cover hinged to swing to open and closed position on said pan, an air delivery pipe connected to said cover and swinging therewith, adapted to deliver air under pressure above a bed of material on 15 said grate, an air supply pipe to which said air delivery pipe is connected, and a swivel joint between said air delivery and supply pipes.

20 6. In a sintering apparatus, a sintering pan having a grate, a cover hinged to swing to open and closed position on said pan, an air delivery pipe connected to said cover and swinging therewith, adapted to deliver air under pressure above a bed of material on 25 said grate, an air supply pipe to which said air delivery pipe is connected, and a swivel joint between said air delivery and supply pipes, a gas ignition pipe connected to said cover and swinging therewith, a gas supply 30 pipe to which said gas ignition pipe is connected, and a swivel joint between said gas ignition and supply pipes.

35 7. In a sintering apparatus, a sintering pan having a grate, a cover hinged to swing to open and closed position on said pan, an air delivery pipe connected to said cover and swinging therewith, adapted to deliver air under pressure above a bed of material on said grate, an air supply pipe to which 40 said air delivery pipe is connected, and a swivel joint between said air delivery and supply pipes, a water delivery pipe connected to said cover and swinging therewith, a water supply pipe to which said 45 water delivery pipe is connected, and a swivel joint between said water delivery and supply pipes.

50 8. In a sintering apparatus, a fixed pan, a cover hinged to swing to open and closed position on said pan, a grate and under pan

at the bottom of said fixed pan hinged to swing downward relatively to said fixed pan, an air delivery pipe extending into the apparatus between the cover and grate adapted to deliver air under pressure above a bed of 60 material on the grate, said air delivery pipe being movable away from its position over the grate, and a stack leading from below the grate.

65 9. In a sintering apparatus, a fixed pan, a cover hinged to swing to open and closed position on said pan, a grate and under pan at the bottom of said fixed pan hinged to swing downward relatively to said fixed pan, an air delivery pipe extending into 70 the apparatus between the cover and grate adapted to deliver air under pressure above a bed of material on the grate, said air delivery pipe being movable away from its position over the grate, and a stack connected to a fixed part of the apparatus, independent of the downwardly swinging 75 grate and under pan, and communicating with the space between said grate and under pan.

80 10. In a sintering apparatus, a fixed pan, a cover, a grate and under pan at the bottom of said fixed pan, hinged to swing downward relatively to said fixed pan, means to force air into said apparatus above said 85 grate, said under pan having an open side and said fixed pan having a downwardly extending side wall adapted to close said open side when the under pan is in closed position, and a stack connected to said downwardly extending side wall of the fixed pan, 90 communicating with the space between said grate and under pan.

95 11. In a sintering apparatus, a fixed pan, a cover hinged to swing to open and closed position on said pan, an air delivery pipe entering through said cover to deliver air under pressure above a bed of material in said pan, a grate and under pan at the bottom of said fixed pan, hinged to swing 100 downward relatively to said fixed pan, and a stack connected to said fixed pan and communicating with the space between said grate and under pan.

105 Signed by me at Boston, Massachusetts, this 12th day of August 1915.
